CLAIM

The ornamental design for a standing soap dish, as shown and described.

DESCRIPTION

FIG. 1 is a perspective view of a standing soap dish, showing our new design, with the shading distinguishing a metallic reflective appearance on all viewable surfaces of the lower section of the standing soap dish that contrasts with a clear plastic appearance in the upper section of the standing soap dish;

FIG. 2 is an end elevational view thereof;

FIG. 3 is a side elevational view thereof; and

FIG. 4 is a top plan view thereof.

The shading in the views is intended to represent a metallic reflective surface on the lower section of the dish as contrasted with the transparent surface for the remainder of the dish.
